Primary Examiner — Kelley Donnelly(74) *Attorney, Agent, or Firm* — Edgar A. Zarins; Nirav D. Parikh; Lora J. Granetzdoerffer**(57) CLAIM**

The ornamental design for a cabinet molding, as shown and described.

DESCRIPTION

FIG. 1 is a front perspective view of a cabinet molding showing my new design; and,

FIG. 2 is an enlarged cross-sectional perspective view thereof.

The broken lines are for the purpose of illustrating the environment of the article only and form no part of the claimed design.

The long and short broken lines which define the bounds of the claimed design form no part thereof.
